DESIGN FOR A FLAG

Giovanni Norberto Bonzani, San Mateo
County, Calif.

Application March 18, 1947, Serial No. 137,726

Term of patent 14 years

(Cl. D29—17)

To all whom it may concern:

Be it known that I, Giovanni Norberto Bonzani, a citizen of the United States of America and a resident of the county of San Mateo and State of California, have invented a certain new, original, and ornamental Design for a Flag, of which the following is a specification, reference being had to the accompanying drawing, forming part of this application, in which:

I claim:

The ornamental design for a flag, substantially as shown.

GIOVANNI NORBERTO BONZANI.
